J. Rogginner

Watson E. Coleman

Attorney

UNITED STATES PATENT OFFICE.

JOHN ROGGINER, OF SAN DIEGO, CALIFORNIA.

TUMBLER LOCK.

Application filed July 21, 1920. Serial No. 397,849.

To all whom it may concern:

Be it known that I, JOHN ROGGINER, a citizen of the United States, residing at San Diego, in the county of San Diego and State of California, have invented certain new and useful Improvements in Tumbler Locks, of which the following is a specification, reference being had to the accompanying drawings.

10 This invention relates to locks, and particularly to that class of locks wherein the key is so formed that upon the insertion of the key in the lock, the tumblers in the lock will be forced to a predetermined position to permit the door to be unlocked upon the turning of the key, and that when the key is withdrawn, the tumblers will be automatically shifted to another predetermined position, which will prevent the unlocking of the lock.

15 The general object of my invention is the production of a lock in which the key cannot be removed from the lock until all the tumblers have been set to a locked position by the key, and wherein immediately upon the removal of the key, the tumblers will shift to a locking position.

20 A further object of the invention is to provide a lock with a plurality of series of tumblers, each series being radially retractible and projectable independently of any other series, and provide in connection therewith a key approximately cruciform in cross section, there being as many fins, ribs or bits on the key as there are series of tumblers, these fins, ribs or bits being adapted to engage the tumblers and radially shift them from a locked to an unlocked position.

25 A further object is to provide means for positively forcing the tumblers to a locked position upon the withdrawal of the key.

30 Another object is to provide a lock of this character wherein it is necessary not only that the key should be placed within the lock but that the key shall be forced to bodily shift all of the series of tumblers a certain predetermined distance until a master tumbler is placed in position where it may be turned, thus providing an additional 35 means for preventing the unauthorized unlocking of the lock and a further means for preventing picking of the lock.

35 Other objects will appear in the course of the following description.

My invention is illustrated in the accompanying drawings, wherein:

Figure 1 is a longitudinal sectional view of a tumbler lock constructed in accordance with my invention and showing the parts in their locked position;

Figure 2 is a like view to Figure 1 but showing the key inserted in the lock and the parts in their unlocked position;

Figure 3 is a section on the line 3—3 of Figure 1;

Figure 4 is an end view of the lock showing the keyhole;

Figure 5 is an elevation of one of the tumblers;

Figure 6 is a top plan view of the lock shown in Figure 1;

Figure 7 is an under side view of the lock shown in Figure 6;

Figure 8 is a sectional view through the barrel 15;

Figure 9 is a diagrammatic sectional view through the barrel 15 to show two series of tumblers;

Figure 10 is a like view to Figure 9 but taken at a plane at right angles thereto to show diagrammatically the other two series of tumblers;

Figure 11 is a side elevation of the key used for operating the lock;

Figure 12 is an inner end view of the lock.

Referring to these drawings, 10 designates the cylindrical casing of the lock, which is associated with a bolt 11 moving in suitable guideways and formed with a notch or recess 12 on its under side. The casing 10 has attached to it the escutcheon plate 13 whereby, as illustrated in Figure 4, the lock is attached to the door or other structure to which it is to be applied by means of screws passed through the openings 14 in the escutcheon plate. The escutcheon plate is shown as being in one piece with the casing of the lock. The cylindrical lock casing 10 is formed on its interior with a slight shoulder 15 adjacent the front end of the lock casing. This lock casing is formed with a plurality of longitudinally extending slots 16 and 16^a, shown as four in number, disposed equi-distantly around the lock casing. Two of these slots, namely the slots 16, are shown as extending to the escutcheon plate. The other two slots need not extend quite so far. Extending laterally, that is circumfer-

entially from the two slots 16, are slots 17. Both of these slots extend from the corresponding slot 16 in the same direction. The slots 16 and 16^a terminate short of the inner end of the casing 10.

Disposed within the casing 10 is a barrel 18 which is rotatable within the casing 10 and fits the casing exactly. The barrel 18 at its end is formed with a shoulder 19 which fits against the shoulder 15, the outer end of the barrel being flush with the outer end of the casing 10, as illustrated most clearly in Figure 1. This end of the barrel is solid for a depth equal to that of the escutcheon plate 13, and this end of the barrel is provided with a cruciform opening 20, as shown in Figure 4. The opposite end of the barrel is closed by an end plate 21 provided with two screw openings. Attached to this end 21 of the barrel is a disk 22, through which screws 23 pass into the screw openings of the barrel, as shown in Figure 7, this disk being rabbeted at its margin to fit over the adjacent extremity of the casing 10, as shown in Figure 1, and being formed with an arm 24 which engages with the notch 12 in the bolt 11 (see Figure 3). This disk 22, therefore, oscillates with the barrel 18 when a key is inserted in the barrel and the barrel is oscillated, and this plate 22 is formed at its center with a central recess 25 to accommodate the extremity of the key, as shown in Figure 2. On its inner face, as shown in Figure 12, this plate 22 is formed with a lug 26 which engages in a notch 27 formed in the casing (see Figure 6) so as to limit the movement of the disk 22 and of the barrel 18 relative to the casing.

That portion of the barrel between its outer end and the end wall 21 is hollow to contain the tumblers and is provided in its walls with four longitudinally extending slots 28. Within the hollow interior of the barrel there are provided a plurality of series of tumblers, shown as four series of tumblers. The positions and arrangements of these tumblers are shown in diagrammatic views in Figures 9 and 10. Each tumbler, as illustrated in Figure 3, is formed of a centrally disposed, approximately rectangular body 29 having oppositely projecting arms 30, these arms being of different lengths, that is one of the arms on each tumbler being longer than the other arm. Both arms of any one tumbler, however, are constantly in engagement with the diametrically opposed slots 28. Thus, in Figure 3, the arms 30 extend vertically with relation to the drawing and the upper arm is shorter than the lower arms, but these arms are both in engagement with the corresponding diametrically opposed slots 28. Each tumbler has a length from the extremity of one arm to the extremity of the other exactly equal 60 to the exterior diameter of the barrel 15 so

that when any one tumbler is disposed in one position in the barrel, neither of its arms will project out beyond the surface of the barrel. When, however, the tumbler is shifted in one direction, its long arm will project 70 beyond the surface of the barrel and project into one of the slots 16 of the enclosing casing.

As before stated, there are four sets of these tumblers, these sets being designated 75 respectively in Figures 9 and 10 as *a*, *b*, *c* and *d*. The sets *a* and *b* are disposed in alternate relation to the sets *c* and *d*, the tumblers *c* and *d* operating through a pair of slots at right angles to the slots through 80 which the arms of the tumblers *a* and *b* operate. It will be understood that each of the tumblers has one arm 30 which is relatively short and the other arm 30 relatively long, it being the long arm which is projected out through the appropriate slot, the short arm being engaged by springs, as will be later described. Each of these tumblers has a central aperture 31 so formed that a certain bit or fin on the key will act to shift 85 that tumbler in a certain direction.

In addition to these four series of tumblers *a*, *b*, *c* and *d*, there is a master tumbler 32, shown in Figure 5, which is formed with two diametrically extending lugs 33, these 90 lugs being bored for the reception of a headed pin 34. The square heads 35 of these pins operate within the slots 16, as shown in Figures 6 and 7. These square heads are nicked transversely to permit a screw driver 100 to be placed in the heads and the heads rotated to unscrew them. When the whole series of tumblers and the master tumbler are shifted forward to the position shown in Figure 2 by means of the key and the 105 key rotated, these square heads 35 are adapted to be shifted laterally into lateral or circumferentially extending grooves 17, and thus the lock may be turned by the key to a position to unlock the door, but in the 110 normal and locked position, these tumbler lugs constituted by the heads 35 will be in the extensions 16^a of the slots 16, as shown in Figures 6 and 7, and will prevent any rotation of the barrel with its tumblers. All 115 of the tumblers are longitudinally movable within the barrel 15 against the action of a spring 36, shown in Figures 1 and 2, which bears against the end wall 21 and against the end tumbler of the series of tumblers, 120 this end tumbler being relatively thick.

The longitudinal extension 16^a of the groove 16 receives the lugs formed by the heads 35 and, as before stated, prevents any rotation of the barrel with its tumblers until 125 the key is forced inward, as shown in Figure 2, forcing the series of tumblers and the master tumbler forward against the action of the spring 36 until these heads 35 are opposite the entrances of the slots 17, where- 130

upon the barrel and the tumblers may be turned in a clockwise direction in Figures 6 and 7 to throw the bolt. Thus when the key is inserted in the lock, it acts as will be hereinafter described to cause the retraction of all the several series of tumblers from the slots 16 of the casing 10, but even then the lock cannot be turned until the key is forced inward, as shown in Figure 2, 10 to shift all of the tumblers and the master tumbler longitudinally against the action of the spring 32 and bring the locking lugs formed by the heads 35 into alignment with the slots 17. Then and only then can the barrel be rotated to an unlocking position.

For the purpose of urging the several series of tumblers to their locking position, that is so that the long arms of the tumblers *a* project in one direction through the slot 20 A (see Figure 9), the long arms of the tumblers *b* in the opposite direction through the slot *b* (see Figure 9), the long arms of the tumblers *c* beyond the walls of the slot C (see Figure 10), and the long arms of the tumblers *d* beyond the slot D (see Figure 10) and, therefore, project the long arms of these several tumblers into engagement with the walls of the slots 16, I provide leaf springs 37 which are disposed in the longitudinally extending slots 16 of the casing, as illustrated in Figures 1 and 2, and which, when the barrel is in its locked position, align with the grooves A, B, C and D of the barrel and engage the corresponding tumblers and cause their projection. Each of these springs is formed at its extremity with a depressed and curved portion 38 which is formed to engage the short arms of the proper tumbler. Thus the spring 37 which is associated with the slot D will force the tumblers *d* outward, that is project the long arms of the tumblers *d*. The spring 37 which is associated with the slot C will force the tumblers *c* in a direction to project their long arms out of the corresponding slot 16 so that whenever the barrel 15 is turned to its locking position and the key withdrawn, these springs 37 will act to force the tumblers radially outward into engagement with the slots 16.

The key illustrated in Figure 11 comprises a handle 39 and a shank which is cruciform in cross section to provide the four bits or fins 40. This shank tapers from its point of connection with the handle to its extremity and fits the cruciform opening 20 in the end of the barrel. Each of these bits 40 is cut to provide a series of alternate depressed and projecting portions 60 on its edge, which portions merge into each other so as to form a relatively sinuous, cam-like edge for each bit which are adapted to engage with the tumblers and are so formed in conjunction with the tumblers 65 that when the key is inserted, all of the tumblers will be shifted to a fully retracted position against the action of the springs 37, as illustrated in Figure 2. In addition to the bits or fins 40, the key is provided inward of its handle with the shoulders 41 which are adapted, when the key is inserted, to engage against the master tumbler 32 or against the end tumbler of the series of tumblers in case the master tumbler is not in the position shown in Figures 1 and 2 so as to cause the series of tumblers to move inward against the pressure of the spring 36 until the lug or lugs formed by the heads 35 on the master tumbler have moved into alignment with the circumferential slots 17. Then and only then can the barrel be turned to retract the bolt.

The operation of the lock is as follows: When the key is retracted, the springs 37 act to force the tumblers radially outward in four different directions and through the four slots in the casing, as illustrated in Figure 1, thus locking the rotatable barrel to the casing and preventing any rotation of the barrel. The rotation of the barrel is further prevented by the fact that the pins or lugs formed by the heads 35 on the master tumbler are disposed in the portions 16^a of the slots 16. Upon the insertion of the key, the edge contour of the fins or bits 40 cause the tumblers to move outward or inward until the key is fully inserted, as shown in Figure 2, when all of the tumblers are retracted from the longitudinal slots 16 of the casing. While the key has fully retracted these tumblers, the lock is not yet ready to be turned until the key is forced inward sufficiently until the shoulders 41 engage with the master tumbler so that the key forces the barrel rearward within the casing until the lugs formed by the heads 35 on the master tumbler are moved into alignment with the slots 17. Then the key may be turned to turn the barrel and retract the bolt. So long as the lock is turned to cause a retraction of the bolt 11 the key cannot be withdrawn. The key can only be withdrawn when the lock is turned to its locked position for the reason, of course, that when the lock is turned the several series of tumblers are all forced inward to the position shown in Figure 2 and engage with the depressions in the key and prevent any pulling out of the key. When the barrel has been turned to a position to permit the retraction of the key and the key is retracted, then as the key is withdrawn, the springs 37 act, as before stated, to project the tumblers into the several slots in the casing.

It will be seen that in order to open this lock, it is not only necessary to have all four sets of tumblers retracted, but that it requires a shifting of all the tumblers forward to clear the lugs on the master tumbler from the extensions 16^a of the slots 16. In

this lock there are four obstructions that would have to be overcome before the tumblers will move. In other words, all four sets of tumblers would have to be set in correct position for unlocking the lock, and still it would be impossible to turn the tumblers because the lug on the master tumblers would project through the longitudinal extension 16^a of the slot 16 of the casing. As 10 the key cannot be removed from the lock until all the tumblers are in such position that they will engage in the slots, there is no danger of the tumblers binding, and as soon as the key is turned to a locking position 15 and removed from the lock, the spring 36 forces all the tumblers to the front of the lock casing, causing the master tumbler to engage the extensions 16^a of the slots 16. The springs 37 are provided as an extra 20 precaution against picking the lock, and to particularly provide a positive means for forcing the tumblers outward. Where the action of the tumblers is controlled by gravity, then the instant the key is withdrawn 25 from the lock, the tumblers either remain stationary or drop to the bottom of their several slots. With this method of controlling the tumblers, each series of tumblers is not only forced into the slot but 30 are held there by the tension of the spring.

While I have illustrated a particular embodiment of my invention, I do not wish to be limited to the details thereof, as these details might be varied in many ways and 35 equivalent details used without departing from the spirit of the invention as defined in the appended claims.

I claim:—

1. A lock comprising a casing, an oscillatable barrel, a plurality of series of tumblers disposed within and carried by the barrel and each series operable in different radial planes, the casing having a plurality of slots with which the different series of tumblers are engageable, and a key having a cruciform shank providing a series of bits, each bit having an edge contour adapted to shift one series of tumblers.

2. A lock comprising a casing, an oscillatable barrel having radial slots, a plurality of series of tumblers disposed within and carried by the barrel and each series operable in different radial planes, the series of tumblers being supported in and guided by said slots in the barrel, the casing having a plurality of slots with which the different series of tumblers are engageable, and a key having a cruciform shank providing a series of bits, each bit having an edge contour adapted to shift one series of tumblers to a fully retracted position when the key is fully inserted and in engagement with all the tumblers.

3. A lock comprising a casing, an oscillatable barrel, a plurality of series of tum-

blers disposed within and carried by the barrel and each series operable in different radial planes, the barrel being formed with slots supporting and guiding the several tumblers, the casing having a plurality of slots with which the different series of tumblers are engageable, a key having a cruciform shank providing a series of bits, each bit having an edge contour adapted to shift one series of tumblers to a fully retracted position when the key is fully inserted and in engagement with all the tumblers, and means for projecting each series of tumblers when the barrel is rotated to a position with the tumblers in alignment with the slots of the casing and the key is withdrawn.

4. A lock comprising a cylindrical casing having a plurality of longitudinally extending slots, a rotatable, hollow barrel disposed within the casing closed at one end, the closed end having a cruciform key opening and the barrel being provided with a plurality of longitudinally extending slots adapted in one position of the barrel to align with the slots in the casing, a plurality of series of tumblers disposed within the barrel, each series of tumblers having two arms movable through and guided by diametrically opposite slots of the barrel, one of said arms being longer than the other arm and each tumbler having a keyway through its center, and a key having a shank cruciform in cross section to provide a series of bits, each bit having an edge contour adapted to engage a certain series of tumblers and cause the projection or retraction of certain tumblers and the complete retraction of all of the tumblers when the key is fully inserted to thereby permit the barrel to be rotated by the key, and means causing the projection of the several series of tumblers into the slots in the casing when the key is retracted.

5. A lock comprising a casing having a series of longitudinally extending slots, a barrel mounted for oscillation in the casing and having means whereby it may be connected to a bolt, the barrel being hollow and closed at its opposite ends, the ends of the barrel being provided with cruciform apertures and the periphery of the barrel being provided with a plurality of longitudinally extending slots, a plurality of series of radially projectable tumblers mounted within the barrel and having arms extending in alignment with said slots, the tumblers being provided with central key apertures, all of said series of tumblers being longitudinally shiftable in the barrel, a spring holding said tumblers against longitudinal shifting movement and toward the key end of the casing, a master tumbler having a central aperture and formed with a lug, the barrel being slotted for the passage of the lug.

- and the casing being formed with a circumferential slot into which said lug engages, and a key cruciform in cross section to provide a plurality of bits, the edge face of each bit being adapted to engage the corresponding tumblers to project and retract the tumblers as the key is inserted and to cause the complete retraction of the tumblers when the key is fully inserted, the key at one point being provided with shoulders adapted to force all of the tumblers longitudinally within the barrel to thereby carry the tooth on the master tumbler out of the longitudinally extending groove in the casing and permit the rotation of the barrel as a whole.
6. A lock comprising a casing having a plurality of longitudinally extending slots, a barrel oscillatably mounted within the casing and adapted to be connected to a locking bolt, the barrel being closed at its outer end and said closed end having a key aperture, said barrel having a plurality of slots equal in number to the number of slots in the casing, a series of flat radially projectable tumblers mounted within the barrel and disposed in contact with each other and each having a pair of arms extending in opposite directions and projecting through and guided by the diametrically opposite slots in the barrel and adapted to project into diametrically opposite slots in the casing, each tumbler having a central key passage, springs urging said tumblers into a projected position, and a key insertible through the aperture in the end of the barrel and engageable through the apertures in the several tumblers to cause the complete retraction of said tumblers when the key is fully inserted.
7. In a lock, a casing formed with diametrically opposite, longitudinally extending slots, a barrel formed with diametrically opposite, longitudinally extending slots and oscillatable within the casing, one end of the barrel having a key aperture, a series of tumblers mounted within the barrel, each tumbler having a relatively long arm projectable through one of said slots and a relatively short arm engaging in the opposite slot, longitudinally extending springs engageable with the outer end faces of the short arms of the tumblers to urge the tumblers in position to project the long arms through the slots of the barrel into the slots of the casing, and a key having a bit adapted to engage and retract said tumblers from their engagement with the slots in the casing when the key is fully inserted.
8. In a lock, a casing formed with diametrically opposite, longitudinally extending slots, a barrel formed with diametrically opposite, longitudinally extending slots and oscillatable within the casing, one end of the barrel having a key aperture, a series of tumblers mounted within the bar-
- rel, each tumbler having a relatively long arm projectable through one of said slots and a relatively short arm engaging in the opposite slot, longitudinally extending springs engageable with the short arms of the tumblers to urge the tumblers in position to project the long arms through the slots of the barrel into the slots of the casing, a key having a bit adapted to engage and retract said tumblers from their engagement with the slots in the casing when the key is fully inserted, the series of tumblers being longitudinally movable within the barrel, a spring urging said tumblers in a direction toward the key end of the barrel, and a master tumbler disposed within the barrel and having a lug projecting beyond the barrel, the casing having an angular slot with which said lug engages, one portion of the lug extending longitudinally of the casing and the inner portion extending circumferentially of the casing whereby, when the key is inserted, the tumblers may be shifted longitudinally to carry the lug on the master tumbler out of the longitudinal slot and into the circumferential portion of the slot to thereby permit the rotation of the barrel.
9. A lock having a casing and a barrel rotatable within the casing, tumblers carried by the barrel and radially projectable into engagement with the casing, a key which, when inserted, retracts said tumblers from engagement with the casing and permits the rotation of the barrel, and means locking the barrel to the casing from rotative movement until the tumblers have been forced longitudinally a predetermined distance toward the rear end of the barrel.
10. A lock having a casing and a barrel rotatable within the casing, tumblers carried by the barrel and radially projectable into engagement with the casing, a key which, when inserted, retracts said tumblers from engagement with the casing and permits the rotation of the barrel, means locking the barrel to the casing from rotative movement until the tumblers have been forced longitudinally a predetermined distance toward the rear end of the barrel and including a master tumbler having a lug, the casing being formed with a longitudinally extending slot and a circumferentially extending slot rearward of the longitudinally extending portion of the slots in which said lug is adapted to travel, and a spring urging the tumblers toward the forward end of the barrel and the master tumbler out of alignment with the circumferentially extending slot.
11. A lock having a casing member and a barrel member rotatable within the casing member, tumblers carried by one of said members and radially projectable into engagement with the other member, a key which when inserted, retracts said tumblers

- out of operative locking position and permits the rotation of the barrel, and means locking the barrel member to the casing member from rotative movement until the tumblers have been forced longitudinally a predetermined distance toward the rear ends of the casing and barrel.
12. A lock having a casing and a barrel rotatable within the casing, means locking the barrel to the casing from rotative movement including a tumbler having a radially projectable lug, the casing being formed with a longitudinally extending slot and a circumferentially extending slot intersecting the longitudinally extending slot inward of its outer end, said lug being adapted to travel in said slots, a spring urging the master tumbler toward the forward end of the barrel with its lug out of alignment with the circumferentially extending slot 20 whereby to require that the master tumbler shall be forced rearward to bring its lug into alignment with the circumferential slot before the barrel can be turned, and a key insertible into the barrel and having a part 25 thereon adapted to engage said master tumbler to thereby shift it longitudinally and a part thereon adapted to engage the master tumbler to rotate it with the barrel.
- In testimony whereof I hereunto affix my 30 signature.

JOHN ROGGINGER.
